UNITED STATES PATENT OFFICE.

WILFRED R. MILNER, OF PONTIAC, MICHIGAN.

DESIGN FOR AN AUTOMOBILE RADIATOR SHELL.

Application filed May 13, 1926. Serial No. 17,688. Term of patent 7 years.

To all whom it may concern:

Be it known that I, WILFRED R. MILNER, a citizen of the United States, and a resident of Pontiac, county of Oakland, and State of Michigan, have invented a new, original, and ornamental Design for an Automobile Radiator Shell, of which the following is a specification, reference being made to the accompanying drawing, forming a part thereof.

In the drawing, Figure 1 shows in perspective my new design of radiator shell applied to the front end of a motor vehicle.

Figure 2 is a front elevation of the shell.

Figure 3 is a side elevation.

I claim:

The ornamental design for an automobile radiator shell as shown.

WILFRED R. MILNER.
